UNITED STATES PATENT OFFICE.

LEONARD C. ROBERTS, OF NUNDA, NEW YORK, ASSIGNOR OF ONE-THIRD
TO SAMUEL G. McTARNAGHAN AND ONE-THIRD TO WILLIAM H. JEFFS,
BOTH OF FILLMORE, NEW YORK.

CONCRETE-MIXING MACHINE.

No. 841,273.

Specification of Letters Patent.

Patented Jan. 15, 1907.

Application filed March 6, 1906. Serial No. 304,568.

To all whom it may concern:

Be it known that I, LEONARD C. ROBERTS, a citizen of the United States, residing at Nunda, in the county of Livingston and State of New York, have invented certain new and useful Improvements in Concrete-Mixing Machines, of which the following is a specification.

My invention contemplates certain new and useful improvements in concrete-mixing machines of that type which are provided with three hoppers for sand, stone, and cement, respectively, and a mixing-drum designed to receive the ingredients from the hoppers and to thoroughly commingle the same, first in a dry state and then wet, the mixed materials being finally discharged from the mixing-drum either in a continuous flow or in batches of predetermined quantities.

The object of my invention is to provide an improved mixing-machine of this character which will embody characteristics of strength, lightness, durability, and efficiency of operation and which will be comparatively cheap to construct, and the invention consists in certain constructions, arrangements, and combinations of parts hereinafter fully described and claimed.

For a full description of the invention and the merits thereof, and also to acquire a knowledge of the details of construction of the means for effecting the result, reference is to be had to the following description and accompanying drawings, in which—

Figure 1 is a side elevation of my improved concrete-mixing machine, partly broken away. Fig. 2 is a top plan view thereof. Fig. 3 is an enlarged transverse sectional view taken approximately on the line 3 3 of Fig. 2. Fig. 4 is a similar view taken approximately on the line 4 4 of Fig. 2. Fig. 5 is a detail cross-sectional view illustrating the shafts of the mixing-drum and the mixing-shovels carried thereby. Fig. 6 is a detail perspective view of one of the shovels, the arm carrying the same being shown in section. Fig. 7 is a detail perspective view illustrating the batch-chamber. Fig. 8 is a detail perspective view of the series of independently-adjustable spring-arms, which together constitute a yielding gate for the discharge ends of the stone and sand hoppers.

Fig. 9 is a fragmentary horizontal section illustrating a portion of said gate. Fig. 10 is a sectional view illustrating one side of the 55 castings for one end of the hoppers. Fig. 11 is an opposite side view thereof.

Corresponding and like parts are referred to in the following description and indicated in all the views of the drawings by the same 60 reference characters.

The framework 1 of the machine is in the present embodiment supported on traveling wheels, as shown, and serves as a platform for a motor 2, which in the present instance 65 is a steam-engine of the vertically-reciprocating type fed with steam from a generator or boiler 3. Extending across the side bars of the framework in spaced relation to each other are two cross-bars 4 and 5 in the form 70 of castings, secured to the side bars of the framework by bolts or the like. These cross-bars 4 and 5 constitute the main supports for the sand, stone, and cement trays for the one end of the mixing-drum and for the three 75 hoppers of the machine.

Referring particularly to Fig. 3, it will be seen that two semicircular plates 6 are arranged side by side between the cross-bars or castings 4 and 5, with their outer flanged 80 edges resting upon and riveted or otherwise secured to said cross-bars. These semicircular plates 6 extend longitudinally and are preferably of sheet-steel or similar light and strong metal or material and constitute the 85 troughs or trays for the sand and stone. The adjacent or inner edges of said plates receive between them the downwardly-extending flange 8 of a Y-shaped sheet-steel trough or tray 9, being bolted to said flange, as shown. 90 The tray 9, as seen in Fig. 3, is smaller than the trays formed by the plates 6 and is located between and somewhat above said plates and is intended for the cement. Each of the trays constituted by the plates 6 and 95 9 may be, if desired, and preferably are, covered with sheet-steel linings 7, intended to receive the wear of the materials, so that when they are worn out by the abrasive action they may be renewed and replaced by 100 others without the necessity of replacing the entire tray.

While I have shown the cement-tray, as well as the other trays, as provided with one

of these linings, I do not deem it necessary that this particular tray be furnished with the lining.

A casting 11 is mounted upon the cross-bar or bracket 5 and with said bar is provided with three lower bearings or boxes 12^a, intended to receive shafts, and with an upper half-boxing 13^a. The hoppers are intended to be supported directly over the cross-bars 4 and 5, with their discharge ends directly over the trays 7 and 8. The hoppers (designated A, B, and C) are in the present instance composed of six pieces of suitably light and strong sheet-steel, which produces a rigid structure which is possessed of the desirable characteristic of lightness. These six pieces comprise two side plates 12, end plates 13, and intermediate plates 14. The side plates 12 are each provided with outwardly-extending angular ends 15, and one of said side plates is recessed on its lower edge to accurately fit the contour of the upper edge of the casting 11, as best seen in Fig. 4, said plate being directly thus supported on said casting. The other side plate is of exactly the same shape as the side plate supported on the casting 11; but its lower edge provides feed-openings for the material to discharge from the hoppers into the mixing-drum, as best seen in Fig. 3. This construction enables both of the side plates to be stamped in the same shape, so that by bending the ends in opposite directions they may be used for either side of the hopper construction and the same dies used for both.

The end plates 13 are secured in place to the outwardly-diverging ends of the side plates by being flanged therearound and bolted thereto, as best seen in Fig. 2. The intermediate plates 14 are secured to the opposite side plates and extend across the same with their lower ends converging and spaced from each other to meet the opposite edges of the tray 9, for which they constitute the hopper C.

By the arrangement described it will be seen that the hoppers A and B, that are intended for sand and stone, are each provided with a transversely-widened mouth portion, enabling the wheel arrows to readily discharge their contents into said hoppers, and that the intermediate hopper C for the cement results in an arrangement whereby the cement-hopper is arranged in a comparatively low plane between the other two hoppers instead of being above the same, where to receive its contents an elevating-conveyer or an elevated platform would be necessary. Hence the operation of discharging the ingredients into the hoppers is facilitated.

In each of the trays 6 there is mounted a conveyer in the form of a worm 16, mounted on a shaft 17, and in the tray 9 there is mounted a conveyer composed of a series of inclined blades 18, mounted upon a shaft 19.

The shafts 17 and 19 extend out through the boxes 12^a, in which they are journaled, while the shaft 19 extends out through the half-boxing 13 of the casting 11. The ends of the said shafts are also journaled in a cross-bar 70 or casting 20, provided with suitable boxings therefor, and the boxing for the shaft 19 is formed in a vertically-extending standard 21, which also forms part of the middle boxing of the three on the bracket or cross-bar 75 20, as best seen in Fig. 4. In connection with these three shafts—namely, the two shafts 17 and the shaft 19—there is another shaft, (designated 22,) which is the main shaft 80 of the machine and is connected at one end to the driving-shaft of the motor 2, as seen in Fig. 2. The shaft 22 is journaled in the middle boxing of the three formed in the cross-bar 20, (shown in Fig. 4,) and it also passes through and is journaled in the middle boxing 12^a of the castings 5 and 11. (Shown in Fig. 10.) At its opposite end the shaft 22 is journaled in a boxing in an end cross-bar 23. (Shown best in Fig. 2.) The shaft 22 is provided with a loose pinion 24, meshing with a 90 similar pinion 25 on one of the shafts 17, and it may be coupled to its pinion 24 by means of a clutch 26. Each of the shafts 17 and 19 is provided with a sprocket-wheel 27, and a sprocket-chain 28 extends around all three 95 sprocket-wheels. By this arrangement as the shaft 22 is rotated by the motor 2 it will drive one of the shafts 17 by means of the pinions 24 and 25, and the said driven shaft 17 will in turn drive the other two shafts 17 100 and 19 by means of the sprocket wheels and chain.

The material fed into the hoppers passes into the bottoms of the hoppers constituted by the three trays before described and by 105 means of the revolving conveyers is carried outwardly into the receiving end of the mixing-drum 29, which is preferably of sheet-steel and is suitably supported in the framework 1 in a longitudinal position therein. 110 In order to insure accuracy of feed, I provide a spring-gate for the discharge ends of the hoppers A and B, that are intended for the sand and stone, said gate acting to properly crowd the materials down into the conveyers 115 to insure that the feed will be maintained at a uniform rate. This spring-gate, as best seen in Figs. 3, 8, and 9, is composed of two series of vertically-extending spring-steel bars 30, the lower ends of which are curved 120 to conform to the cross-sectional contour of the conveyers. These spring-bars are all held with their lower ends slightly spaced from the upper sides of the conveyers and below the lower edge of the rearmost side plate 125 of the hopper construction, as best seen in Fig. 3, by means of a transverse clamping-bar 31, which extends across the outer sides of the bars 30 near their upper ends, and by means of bolts 32, extending between every 130

two bars and secured to the rearmost end plate of the hopper construction, securely binds all of said bars in the proper position and at the same time provides means whereby any one of the bars may be adjusted vertically independently of the others or may be removed and replaced by a fresh bar should any of the bars become broken or need repair. As shown best in Fig. 11, the inner side of the casting 11 is provided with curved flanges 33, so that the material fed into the trays will not work into the bearings of the shafts 17, because said flanges 33 extend around the upper sides of the conveyers at one end thereof.

The shaft 22, in addition to being the driving-shaft for the conveying mechanism that feeds the materials to the mixing-drum, is the shaft which carries the mixing devices. These in the present instance comprise shovels 34, carried on the ends of radial arms 35, which are secured to the shaft in any desired manner, as by the socket-pieces 35^a. As best seen in Fig. 2, the shovels are arranged in a plurality of longitudinally-extending series, the shovels of one series being staggered with relation to the other series. Each of the shovels 34 is of peculiar formation, as best seen in Fig. 6. Each shovel comprises two wings 36, extending on opposite sides of the arm 35, the rearmost wing being approximately twice as large as the foremost wing, or that wing which is adjacent the receiving end of the mixing-drum. Each wing is slightly bent upwardly at its outer edge, as indicated at 37, and each wing is further provided at its rear corner or end with a portion slightly bent up, as indicated at 38. By means of this particular construction of shovel as the shovels revolve in the drum they will catch up the material and throw it inwardly away from the wall of the drum instead of scraping it along said wall, while at the same time a large portion of the material acted upon by each shovel will be thrown rearwardly toward the discharge end of the drum, while the remainder will be thrown in the reverse direction toward the feed end or receiving end of the drum, so as to be acted upon again by the same shovel and succeeding shovels. Hence it will be seen that a thorough commingling of the ingredients will be effected, because the shovels will not scrape the material rearwardly along the walls of the drum, but will throw it upwardly and toward the center, where it will be caught by the succeeding shovel and a thorough back-and-forth agitation effected. At the receiving end of the mixing-drum the materials are commingled in a dry state and then are preferably mixed wet by means of a spray-pipe 39, which may supply steam or water.

At the discharge end of the mixing-drum I have provided a batch-chamber, which in

the present instance is composed of a sheet-metal angular body 40, bolted to the end of the drum and projected outwardly therefrom, as shown in Fig. 2. The said body is intended to contain a batch of concrete of predetermined size—say one-half of a yard—and is primarily intended for the top dressing. It is rectangular in shape, as shown, and is provided with a bottom-discharge opening the side walls of which are inclined. An end gate 41 is hinged at opposite sides by means of ears and studs to the opposite sides of the body portion 40 and is provided with an angular lower portion 42, terminating in a forwardly-extending angular edge 43. The end gate 41 may be swung toward the body portion and away from the same to close and open the discharge end of the body portion in any preferred manner. The means here shown for this purpose comprises a rod 44, secured to the end gate and having either one or both ends connected to hand-levers 45, fulcrumed intermediate their ends on the sides of the framework. The end gate 41 is formed in its angular portion 42, and preferably at a point below the bottom of the mixing-drum, with a somewhat semicircular opening 46, controlled by a revoluble closure 47.

It is to be understood that when the machine is operating as a continuous machine the end gate 41 is held in an open position, so that the mixed materials may be continuously discharged through the mouth or discharge-opening of the batch-chamber; but when it is desired to operate the machine as a batch-mixer—for top dressing, for instance—the end gate 41 is closed. By means of the angular portion 42 of the end gate with its angular edge 43 the closing movement of the end gate will bring said edge 43 underneath and past the lower rear edge of the mixing-drum, or rather the lower rear edge of the body portion 40 of the batch-chamber, with a somewhat shearing action, and this action will result in forcing the material upward and backward into the mixing-drum and will avoid any clogging such as would result if it were attempted to close the end gate merely with an abutting action against the body portion of the batch-chamber.

As it is important that the top dressing shall contain no lumpy substances and as such substances by their own weight tend to lie along the bottom of the mixing-drum, I provide the draw-off opening 46. This opening after it has subserved its purpose for the time being may be closed by turning the closure 47 in a direction to close the lower end of the opening first and thence to the upper end, the closing movement being effected in an upward direction. Hence as the closure 47 is turned upwardly to close the opening 46 its advancing edge in the closing action will sweep upwardly through the outpouring materials and assist the easy closing

of the said closure 47, whereas if the closure 47 turned in an opposite direction it would tend to clog.

As best seen in Figs. 1, 2, and 3 and as above described, the conveyer for the cement embodies a series of angular blades 18, mounted upon the shaft 19, instead of a continuous worm or screw. By the provision of a conveyer of this character for the cement it is manifest that no matter how lumpy the cement may be when it is received for action by the blade conveyer, as it is most liable to be lumpy in damp weather, for instance, the blades being separate from each other will effectively chop the cement and insure that it shall be discharged into the mixing-drum in a comminuted or pulverized condition.

Having thus described the invention, what is claimed as new is—

- 20 1. In a concrete-mixing machine, a mixing-drum, a shaft mounted to rotate in said drum and extending longitudinally thereof, arms extending radially from said shaft and arranged in a plurality of longitudinally-extending series, the arms of one series being staggered with relation to the arms of the other series, means for turning said shaft, and shovels on the outer end of each arm, each shovel embodying two oppositely-extending curved wings of different sizes, whereby a portion of the material acted upon by each shovel will be thrown inwardly and rearwardly for successive action thereon by the same shovel, while the remainder of the material acted upon by said shovel will be
- 25
- 30
- 35

thrown in the opposite direction toward the next shovel of the adjacent series.

2. In a concrete-mixing machine, the combination of a mixing-drum, mixing devices therein and means for actuating the same, and a batch-chamber at the rear end of the mixing-drum, said chamber comprising a body portion projected rearwardly from the end of the mixing-drum, and a hinged end gate pivotally mounted to the body portion by its upper edge and provided with an angular lower end and a forwardly-extending angular edge flange, designed to shut across the lower edge of the body portion, as and for the purpose set forth.

3. In a concrete-mixing machine, the combination with a mixing-drum, mixing devices therein, and means for actuating the mixing devices, of a batch-chamber comprising a body portion secured to and projected from the rear end of the mixing-drum, an end gate for said body portion and designed to close a discharge-opening therein, said end gate being formed with a draw-off opening, and a closure for said opening, said closure being designed to close the opening from the lower end of the same, toward its upper end, as and for the purpose set forth.

In testimony whereof I affix my signature in presence of two witnesses.

LEONARD C. ROBERTS. [L. S.]
